CARTON OR SIMILAR ARTICLE

Thomas Biallo, 430 E. 56th St.,
New York, N.Y. 10022

Filed May 20, 1968, Ser. No. 12,013

Term of patent 14 years

Int. Cl. D9—04

U.S. Cl. D9—230

FIG. 1 is a perspective view of a carton embodying my new design;

FIG. 2 is a side elevational view, the opposite side being a mirror image of the side shown;

FIG. 3 is a front elevational view;

FIG. 4 is a bottom plan view;

FIG. 5 is a top plan view; and

FIG. 6 is a perspective view with the top in a partially opened position.

The back is plain and unornamented.

I claim:

The ornamental design for a carton or similar article substantially as shown and described.
